UNITED STATES PATENT OFFICE.

WILLIAM C. LANGDON, OF WICHITA, KANSAS.

POWER-OPERATED AWNING.

1,413,596.

Specification of Letters Patent. Patented Apr. 25, 1922.

Application filed April 27, 1920. Serial No. 377,008.

To all whom it may concern:

Be it known that I, WILLIAM C. LANGDON, a citizen of the United States, and resident of Wichita, in the county of Sedgwick and

5 State of Kansas, have invented certain new and useful Improvements in Power-Operated Awnings, of which the following is a specification.

My invention relates to power operated 10 awnings, and its general object is to provide means whereby a movable awning may be moved to any desired position by merely opening and closing a valve.

An incidental object is to provide automatic means for locking the awning in any desired position, and automatically releasing the locking means when the awning is initially moved.

In the practice of the invention I employ 20 as the motive power a fluid under pressure, and as air has certain advantages for the purpose I have illustrated an air-pressure system in the accompanying two sheets of drawings, in which—

25 Fig. 1 is a sectional elevation of a preferred construction for a power-operated awning; Fig. 2 is a diagrammatic plan view, partly broken out; Figs. 3 and 4 are sectional detail views; Fig. 5 is a detail view 30 of the brake, its cylinder and connections; Figs. 6, 7 and 8 are sectional plan views of an operating valve in three positions, Fig. 7 being the neutral, the section being made on line B—B, Fig. 9; Fig. 9 shows the operating valve half in section, with connections; Figs. 10, 11 and 12 are plan views of 35 said valve in positions corresponding to Figs. 7, 6 and 8; Fig. 13 is a diagrammatic elevation of air connections viewed on arrow 40 x Fig. 1.

Referring to Figs. 1 to 4 inclusive: 1 is a horizontal shaft carrying the awning roller 2, to which one end of the awning 3 is fastened. A helical torsion-spring 4 is fixed 45 within roller 2 and is tensioned by drawing the awning outward. The outer edge of the awning is fastened to a bar 5, secured to a number of rack-bars 6. Each slide-bar is supported in and by a box guide 7 which is shown as a rolled metal form. Said guides 50 7 are rigidly supported at the desired angle by the front of the building and by the rear portion of window enclosure 8, these latter supports being omitted for clearness.

55 Each rack-bar 6 is preferably a T beam, positioned with centre flange 6' down, and

gear teeth 9 are cut the full length of each flange 6'. Friction is almost entirely eliminated by means of rollers 10 carried by inner ends of bars 6, and rollers 12 journaled 60 in outer ends of box guides 7.

Under the awning roller 2 and below guides 7, is a horizontal rotary shaft 14, journaled in bearings (not shown) mounted on the window casing 16. Keyed on said 65 shaft are spur pinions 17, meshing the respective rack-flanges 6'. This construction insures the uniform travel of the awning as it is moved in or out by spring 4 or the other means to be described.

The awning frame bar 5 is actuated outwardly by a piston rod 18 entering a long cylinder 19 through a stuffing-box 19', rod 18 having a double-packed piston 20 slidably fitting the cylinder. Rod 18 is secured 70 to bar 5 at 21. Cylinder 19 is supported at its outer end by being fitted in a hole cut in the front 22, also rearwardly by supports not shown. This cylinder is connected with a compressed-air reservoir 23 and with an 75 operating valve N, by tubing to be described. For operation by liquid pressure of course the reservoir 23 is unnecessary.

The operating valve is sufficiently shown in detail by Figs. 9 to 12, inclusive. It 80 comprises a cylindric body 24 having on its bottom 25 a seat in which are seven circular ports. The valve proper (26) fits said seat on 25 and has a stem 27 on which is the hand-lever 28. The valve is pressed 85 to its seat by several springs 29 held in position by pins 30 entering a disk 31, held down by the valve-body-cover 32. The under face of valve 26 is formed with three separate segmental ports a, b, c, and a radial port d 90 opposite the middle port b. The ports in part 25 are lettered on the drawing from e to k, inclusive. From port j a tube 33 leads to the outer end of the main cylinder 19. From port h a tube 34 leads to the other end 95 of said cylinder. Short exhaust tubes 35, 36 are connected to ports g, i, respectively, these tubes being open to atmosphere.

From reservoir 23, a tube 37 leads to port k in the valve seat part 25.

With the valve at neutral (Fig. 7) the compressed-air supply is cut off from the cylinder as port b has no communication with port a or port c. Now suppose the awning to be in rolled-up position: to extend the awning, the operator turns the valve to position shown in Fig. 8. This ad-

mits compressed air to port *h*, tube 34 and inner end of cylinder, and simultaneously connects outer end of cylinder through tube 33 and ports *j*, *i*, to atmosphere. Piston 20 is thus propelled outward, and may be arrested at any point by turning valve handle 28 to normal. To retract the awning, the valve is turned from neutral to position shown by Fig. 6. This admits compressed air to port *j* and tube 33, and connects tube 34 and port *h* with exhaust port *g*.

There will of course be some leakage of fluid around piston 20 when the awning is extended; such leakage would permit the piston and connected parts to creep inwardly, due to the force exerted upon the awning by torsion spring 4. To obviate such creeping, I provide a spring-set fluid-released brake, shown by Fig. 5 in detail. At any point on shaft 1, I key a brake-drum 40. A brake-band 41 is secured to any fixture 42 and connects with a piston-rod 43 and piston 44 in a fixed cylinder 45. An expansion spring 46 urges piston 44 outward, thus tensioning band 41 on drum 40. A port 47 in cylinder 45 is connected to a T 48, to which a tube 49 is connected, said tube leading to valve N, to port *e* thereof. T 48 also connects with two branch tubes 50, 51, in which are respective check-valves 52, 53, opening in directions indicated. These tubes are respectively connected with tubes 33, 34, as shown on Fig. 1; the latter supplying compressed air to main cylinder 19.

Port *f* in valve seat part 25 is connected to atmosphere, for exhausting brake-cylinder 45. Operation:—When valve N is at neutral, air pressure is cut off from brake cylinder. When valve is turned to either right or left, air pressure is admitted into tubes 33, 34, thence into tubes 50, 51, in one of which it will be cut off by a check-valve 52 or 53, but will pass through the other and enter cylinder 45, pushing out piston 44 and slackening the brake. When the awning reaches desired position, valve N is turned to neutral; this cuts off pressure from brake piston and simultaneously opens exhaust port *e* to tube 49, through which the air is expelled from brake-cylinder 45 by spring 46, which spring re-sets the brake.

The system here shown may easily be

adapted for water or oil pressure operation by extending the exhaust tubes to a drainage point or to an oil receptacle.

Having described my invention, I claim as new:

1. In a roller awning, an awning frame mounted for inward and outward travel in its own plane, guides for said frame, a piston-cylinder mounted parallel to the line of travel of the awning-frame, the length of said cylinder being greater than said travel; a piston in said cylinder, a rod secured to said piston and extending through a stuffing-box; parallel reciprocative rack-bars in said frame, a transverse bar connecting the forward ends of the rack-bars; said piston-rod being secured to said transverse bar; a manual operating-valve, a valve-seat provided with exhaust-ports and with a connection to a source of fluid under pressure, and tubes for conveying fluid between the respective ends of said cylinder and said valve.

2. In combination, a roller awning, a reciprocal awning-frame, a horizontal shaft rotated by travel of said frame in either direction, a brake-drum on said shaft, a spring-set, fluid-released brake-band upon said drum, means for shifting the awning frame to any position between open and closed by fluid-pressure, said means comprising a manual operating-valve, and means whereby said brake-band is made slack by actuation of said valve to shift the awning in either direction.

3. In combination, a rotary shaft, pinions on said shaft, rack-bars each meshing with said pinions, a bar transverse to the rack-bars and secured thereto, means to actuate the transverse bar, an awning attached to said bar, a brake-drum keyed on said shaft, a brake-band on said drum, a cylinder, a piston therein, a piston-rod connecting the piston to the brake-band, a spring tending to set the brake and opposing the fluid-pressure in the cylinder, and means for admitting fluid to the cylinder and venting fluid therefrom.

WILLIAM C. LANGDON.
